(57) **CLAIM**

The ornamental design for a dispenser for back of high chair and other surfaces, as shown and described.

DESCRIPTION

FIG. 1 is a perspective view of a dispenser for back of high chair and other surfaces showing my new design.

FIG. 2 is a perspective view of the dispenser of FIG. 1 showing the dispenser in its open position.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is a perspective view of another embodiment of the dispenser for back of high chair and other surfaces of FIGS. 1-8 showing my new design.

FIG. 10 is a perspective view of the dispenser of FIG. 9 showing the dispenser in its open position.

FIG. 11 is a front elevational view thereof.

FIG. 12 is a rear elevational view thereof.

FIG. 13 is a left side elevational view thereof.

FIG. 14 is a right side elevational view thereof.

FIG. 15 is a top plan view thereof; and,

FIG. 16 is a bottom plan view thereof.

The broken lines showing a high chair are for illustrative purposes only and form no part of the claimed design.
